UNITED STATES PATENT OFFICE.

JAMES M. GREEN, OF CHICAGO, ILLINOIS.

NON-SKID ATTACHMENT FOR AUTOMOBILE-TIRES.

Specification of Letters Patent. Patented Aug. 10, 1920.

1,348,992.

Application filed May 23, 1918. Serial No. 236,247.

To all whom it may concern:

Be it known that I, JAMES M. GREEN, a citizen of the United States, residing at 2049 Harrison street, in the city of Chicago, in the county of Cook and State of Illinois, have invented certain new and useful Improvements in Non-Skid Attachments for Automobile-Tires, of which the following is a specification.

10 My invention relates to removable non-skid attachments for automobile tires, and has for its objects, the providing of a non-skid attachment which may be easily and quickly put on or taken off without the use 15 of extra tools; one which is securely locked in place when once adjusted against accidental removal or loss; one which is low in cost; one which produces very slight wear on the tire; one in which breaks may be 20 easily, cheaply and quickly repaired; one which has sufficient play to shake lose any dirt or matter which may lodge in it; and one which has no angles or pockets where dirt or snow or ice may permanently lodge 25 to the detriment of its efficiency.

With the above and other objects in view, my invention consists of the novel construction, combination and arrangement of parts as are more fully illustrated and described 30 in the accompanying drawings and specifications hereunto appended.

In the annexed drawings, in which like numerals of reference refer to similar parts,

Figure 1 is a fragmentary elevation of an 35 automobile wheel illustrating the present invention applied thereto.

Fig. 2 is an enlarged plan view of one of the non-skid blocks employed by me.

Fig. 3 is a section view of the non-skid 40 block shown in Fig. 2 taken along the line a—a.

Fig. 4 is a section view of the non-skid block shown in Fig. 2 taken along the line b—b.

45 In illustrating my said invention, I have shown a portion of the rim 1 of an automobile wheel, which may be of any usual construction, having the tire 2 attached thereto in any of the customary methods. As 50 shown, my non-skid attachment, consists of a number of non-skid blocks 3, having a circular body portion 4 bearing against the tire, the inner surface of which is concave, as at 5, with the edges rounded as at 6 in 55 order to reduce the wear caused by contact

with the tire to the least possible minimum. A rib 7 extends the length thereof which is designed to secure the greatest grip upon the roadway, to prevent slipping or skidding. These ribs 7 extend beyond the edge 60 of the body portion 4, and in each end thereof have the holes 8 adapted to receive the rings 9 which connect the non-skid blocks together into a continuous string of any desired length. At one end of said string of 65 non-skid blocks I have preferably attached a larger ring, as 10. At the reverse end of said string of non-skid blocks, I have preferably attached a snap hook, as at 11, which is adapted to snap into the ring 10 or any 70 other ring of said string of non-skid blocks and rings desired in order to attach said string of non-skid blocks upon said tire against accidental detachment or loss. Where the ribs 7 join the body 4, as at 12, I 75 have provided fillets, in order to eliminate the possibility of dirt, snow or ice collecting on said non-skid blocks, and diminishing their effectiveness in gripping the roadway.

80 The chain-like device is provided at one end with a ring 10 and the opposite end is provided with a snap hook 11. The method of attaching the chain-like device is to first 85 pass the end provided with the ring 10 between the spokes of the wheel. The end having the snap hook 11 is then passed through the ring and the chain-like device pulled upon, forming a slip knot about the ring and tire. The chain is then wound 90 about the rim and tire until the end having the snap hook 11 is brought into proximity to the ring 10 and snapped into engagement with the latter. If the chain-like device 95 should be too long or too short to provide for an effective connection between the ring 10 and snap hook 11, the snap hook could be caught into some link of the chain-like device in proximity to the ring 10. To remove the device, the snap hook is released 100 from the ring 10, and the device is unwound from the tire, and removed from the ring 10. While I have described what I consider the simplest and most effective manner 105 of attaching my device to a tire, it is apparent that it is possible to attach it in many other ways, which may appear to the owner to be fully as effective as that illustrated.

When attached to the tire, as explained above, my device forms a continuous row 110

of my non-skid blocks about the tire, with the ribs in contact with the roadway. As the blocks are concaved on the inner surfaces, there is little or no wear on the tire, and at the same time they have a large bearing surface upon said tire. As the rings 9 all lie flatly against the tire, they present no sharp or raised projections to wear the tire, as with ordinary chains, and in addition, have a large bearing surface against the tire, insuring additional gripping surface both against the roadway and the tire. As these rings are of reasonably fair sized diameter, they present little opportunity for dirt or snow or ice to lodge in them, and if it should find lodgment, the vibration of the rings against the tire, as the wheel rotates, would loosen such matter, and it would fall out. I have also, as will be seen, provided fillets where the ribs adjoin the body of the blocks, thereby preventing lodgment of any dirt or ice or snow in the angles thereformed, as might occur, if such angles were sharp or deeply recessed.

By constructing my said non-skid blocks with forming dies, or by casting them, it will be apparent that they can be produced at very low cost, and by connecting them by means of the simple inexpensive rings, with the snap hook at the end, I have provided simple, efficient and inexpensive construction throughout. Again, in case of breakage of a ring, or block, such ring or block may be easily, and quickly removed without special tools, and either another put in its

place, or the remaining rings and blocks connected making the device as usable as before.

While I have shown my device with the ribs having comparatively squared edges, it is apparent that these may be made of different shapes to suit different conditions of the roadway.

It will be further seen, that when removed from the tire, my device may be folded up and packed away in a very small space, thus facilitating its being always carried in the tool box.

Having thus described my said invention, what I claim, and desire to secure by Letters Patent, is the following:

A non-skid chain for motor vehicle wheels adapted to be spirally wrapped around the tire and rim of a wheel and including anti-skid link members consisting of a body having an inner face to fit the tire and provided at its outer face with a rib extending longitudinally of the chain and disposed diagonally of the tread of the tire when the chain is in position thereon, said ribs being extended beyond the body and having openings, and connecting links passing through the openings of the ribs.

In testimony whereof, I have hereunto set my hand in the presence of two subscribing witnesses.

JAMES M. GREEN.
